UNITED STATES PATENT OFFICE.

EDWARD V. WURTS, OF PITTSBURGH, PENNSYLVANIA, ASSIGNOR TO STEEL UTILITIES,
INCORPORATED, A CORPORATION OF NEW YORK.

MACHINE FOR OPERATING ON STRUCTURAL BEAMS.

1,241,259.

Specification of Letters Patent. Patented Sept. 25, 1917.

Application filed August 8, 1914. Serial No. 855,816.

To all whom it may concern:

Be it known that I, EDWARD V. WURTS, a citizen of the United States, residing at Pittsburgh, in the county of Allegheny and State of Pennsylvania, have invented certain new and useful Improvements in Machines for Operating on Structural Beams, of which the following is a specification.

The invention relates to machines for cutting beams, such as coping and notching the beams, preparatory to fabrication and to means and mechanisms coöperating with such machines in the handling and preparation of the beams. The further objects and purposes of the invention will be in part obvious and in part will be set forth hereinafter.

The invention consists in the novel parts, constructions, instrumentalities, combinations and improvements herein shown and described.

The accompanying drawings, referred to herein and constituting a part hereof; illustrate one embodiment of the invention and with the description serve to explain the principle thereof.

Of the drawings:

Figure 1 is a plan, with parts broken away and parts in section of a machine embodying the invention;

Fig. 2 is a vertical central section on Fig. 1, looking toward the top, but with certain internal parts and the right hand end in elevation;

Fig. 3 is an elevation looking at Fig. 2 from the right;

Fig. 4 is a section, on an enlarged scale, on line A—B of Fig. 2, looking in the direction of the arrows;

Fig. 5 is a section, on an enlarged scale, on line C—D of Fig. 2 looking in the direction of the arrows;

Fig. 5^a is a section on line T—U of Fig. 2, looking in the direction of the arrows;

Fig. 6 is a fragmentary view, on an enlarged scale, of a part of the right hand end of Fig. 2, but showing the mechanism after the flanges of the beam have been cut;

Fig. 7 corresponds generally to Fig. 6, but shows the mechanism in position after the web cut has been made;

Fig. 8 is a section on line E—F of Fig. 7 looking in the direction of the arrows;

Fig. 9 is a fragmentary sectional view (on line I—K Fig. 10) showing the cutters prior to making the cuts in the beam flange;

Fig. 10 is a sectional view on line G—H of Fig. 9 looking in the direction of the arrows;

Fig. 11 corresponds to Fig. 9 but shows the position of the parts after the cuts have been made in the beam flange (taken on line N—O of Fig. 12);

Fig. 12 is a sectional view on line L—M of Fig. 11;

Fig. 13 is a fragmentary sectional view showing the same parts as in Fig. 11 but in the position after the cut has been made in the beam web;

Fig. 14 is a part sectional and part elevational view on line P—Q of Fig. 13;

Fig. 15 is a sectional view on line R—S of Figs. 13 and 14;

Fig. 16 is a fragmentary view of the end of the coped beam;

Fig. 17 is a general lay out, somewhat diagrammatic in character, showing the mechanism for coping both ends of the beam, and showing beam numbering, cutting and punching mechanisms and the beam supplying and transporting devices;

Fig. 18 is a fragmentary layout showing the mechanisms arranged to simultaneously cope both ends of a positioned beam; and

Fig. 19 is a fragmentary detail showing vertical adjustment for the feed roll for beams of different sizes having flanges of different widths.

Referring to the accompanying drawings, illustrating by way of example one embodiment of the invention, means are provided for traveling a beam or shape α to the cutting mechanism, and positioning it both longitudinally and transversely preparatory to being notched, coped or otherwise cut, and means are also provided for traveling or transporting the beam away after the completion of the operation.

An embodiment of the mechanism will be first described for coping one end of the beam, and at a later point mechanism will be described for coping or otherwise cutting both ends of the beam in connection with mechanism for traveling and registering or positioning the beam with respect to the mechanisms for coping or otherwise cutting both ends with a minimum amount of mechanism and a minimum handling of the beams.

In Fig. 1 of the drawings, means are provided for feeding the beam both to and away from the coping devices, the embodied form

thereof comprising a series of rolls 1, preferably horizontally arranged in a series for feeding the beam α longitudinally or endwise. The rollers 1 are mounted in bearings 5 2 carried upon the frame 3. The shafts of the rollers 1 are provided at one end with beveled gears 4, said gears meshing with beveled gears 5 fixed upon a driven shaft 6, said shaft 6 may be driven continuously or 10 intermittently and also in both directions, as may be found necessary in operating the machine. A similar mechanism and arrangement of rollers and driving mechanism are provided on the opposite side of the coping device for feeding away the beam where it is desired to discharge it by running it forward, or where it is desired to 15 travel and position it with respect to a coping device for operating upon the other end of the beam.

Referring now more particularly to the coping mechanism proper, means are provided for cutting off the flanges and for beveling the web at both sides of the beam from one positioning of the beam. In accordance with one feature of the invention also, means are provided for successively making the various cuts, rapidly one after the other, while the beam is so positioned.

30 Means are also provided by the invention for varying the relative position or distance between the groups of cutters for beams of different sizes, and in the embodied form, this is effected by moving or positioning the 35 group or groups of cutters for the flange and web on one side of the beam toward or away from and with respect to those on the other side of the beam.

Referring to the illustrated embodiment, 40 a head 11 is mounted in the frame 10 and is held from movement therein by suitable means, such as the pins 12. So far as concerns many features of the invention, it could be utilized for cutting only one side of the beam, but in accordance with other features 45 of the invention, as already indicated, means are provided for cutting both sides of the beam and thus completing the operation, and the mechanism will be so described. 50 The head 11 is conveniently divided horizontally into two parts 13 and 14, there being thus provided an opening therebetween through which the web of the beam α passes.

There is a head 15 arranged contiguously 55 to the head 11, and having likewise two parts 16 and 17 with an opening therebetween through which the web of the beam α passes, the construction being like that of the head 11. The head 11 carries a group or groups 60 of cutters for cutting the flanges and web at one side of the beam, and the head 15 carries a group or groups of cutters for cutting the flanges and web on the other side of the beam.

65 Means are provided for moving the head

15 toward and from the head 11 to take beams of different sizes. In the embodied form of such means, the upper part 13 of the head 11 is provided with an internally screw threaded aperture, within which aperture is a sleeve 20, said sleeve having an external screw thread engaging the internal screw thread of the aperture. The upper portion 16 of the head 15 is likewise provided with an internally screw threaded 75 aperture, and the sleeve 20 passes within said aperture and has an external screw thread engaging said internal screw thread of the aperture, but the screw thread on the sleeve 20 engaging with the part 13 is left 80 handed and that engaging with the part 16 is right handed, or vice versa. Thus, when the sleeve 20 is rotated, and the head 11 is held against rotation, the head 15 will be moved toward or from the head 11 to effect 85 the desired positioning of the two heads for the particular size beam upon which the machine is to operate, and thereby the machine is adapted to operate upon beams of all sizes.

90 A similar construction is provided at the opposite ends of the heads 11 and 15, the part 14 having a similar screw threaded engagement with a sleeve 21, the sleeve 21 also being in screw threaded engagement with 95 the part 17 of the head 15, as shown in Figs. 2, 6 and 8. The screw threads on the sleeve are also reversely cut the same as on the sleeve 20 as already described. the upper and lower halves of the heads 11 and 15, 100 respectively, are thus kept together.

105 In accordance with certain features of the invention, as already indicated, the cuts in both the flange and web are made in succession, and preferably not only are the various cuts on one side of the beam so made successively, but the various cuts in the flanges and web on both sides of the beam are made successively, thus economizing the power required to operate the machine and 110 greatly reducing the strain placed thereon. In the embodied form of cutting mechanism, the part 13 of the head 11 is provided with a stationary cutter 25, having a vertical cutting edge 26 for cutting the flange on the 115 upper side of the web, (referred to Fig. 10). On the opposite or bottom side of the web, (Figs. 10 and 11) is a cutter 27 having a cutting edge 28 for cutting the beam flange on the lower side of the web (referred to 120 Fig. 10).

125 Mounted in the upper part 13 of the head 11 is a reciprocable cutter carrying member 30 provided with a cutter 31. The cutter carrier 30 is reciprocably mounted with its upper edges working beneath the guides 10^a and its bottom surface moving upon or with another cutter carrier 35^b, to be described later (see especially Figs. 2 and 5^a). The cutter 31 has a cutting edge 32 adapted to 130

- coöperate with the cutting edge 26 on cutter 25 to cut the upper portion of the beam flange, and a cutting edge 29, adapted to cut the flange immediately above the juncture thereof with the web. Said cutter 31 is also provided with a horizontal cutting edge 33 for cutting the beam web at a bevel from the cut in the flange to the end of the beam (as shown in Figs. 11 and 13). The cutter 31 is preferably given a rake or slant as shown in Fig. 9 whereby a shearing cut may be given, beginning at the end of the flange and going inward along the web the length of the horizontal cutting edge 32 and then transversely from the web to the outside of the flange. The web of the beam serves as the opposing surface to the horizontal cutting edge 32 in cutting the flanges along the web.
- 20 A cutter carrier 35^b is reciprocably mounted on the lower part 14 of the head 11, its lower edges sliding on top the guides 10^b (Figs. 2 and 5^a). Said cutter carrier 35^b is provided with a cutter 35. Said cutter 35 has a cutting edge 36 adapted to coöperate with the cutting edge 28 of cutter 27 to cut the beam flange below (Figs. 10 and 12). Said cutter 35 has also a horizontally disposed cutting edge 37 adapted to cut the flange away from the web similarly to the cutting edge 32 of cutter 31 but also adapted to coöperate with the cutting edge 33 of cutter 31 to cut the web of the beam at a bevel from the cut end of the flange to the end of the beam. The same kind of rake or slant is preferably given to cutter 35 as was given to cutter 31 to secure a shearing action, and the cutter 31 is in advance of the cutter 35 in the direction of their cutting movement, whereby the cuts made along the juncture of the flange and web by cutting edge 29, and across the beam flange by the cutting edges 26 and 32 are made prior to the cuts made along the juncture of the flange and the opposite side of the web by cutting edge 37, and across the flange by the cutting edges 28 and 36. By this means also the cutting edge 33 is brought into position to coöperate with the cutting edge 37 in the subsequent cutting or trimming of the web.
- For the purpose of effecting the cutting movement between the cutting edges 33 and 37, in cutting or trimming the web, the cutter 35 is mounted for vertical reciprocation in the carrier 35^b, the actuating mechanism therefor being later described. The head 15 is provided with a similar group of cutters, which need not be described in detail and which are designated by reference numerals 25^a to 37^a, as required. Thus, means are provided whereby at a single operation the flange is cut off at either side of the web and the web is cut or trimmed, and not only is this effected for one side of the beam, but both sides thereof at the one operation and at one positioning and stopping of the beam. Also, these operations are performed in succession and with great rapidity and with but a single stoppage the beam is ready for the next operation from the punching or other machine.
- In accordance with one feature of the invention, the same means are utilized for both regulating the distance between the heads 11 and 15, and for actuating the cutters during the cutting operation, although so far as concerns other features of the invention, different means may be employed for these purposes. As embodied, a cross head 40 is reciprocably mounted in the frame of the machine, said cross head being mounted between guides 10^a above and guides 10^b below. Shafts 41 and 42 are rotatably carried by the cross head 40, but are restrained from longitudinal movement relatively to the cross head by suitable means, such as collars 43 and nuts 44. The shafts 41 and 42 pass through the sleeves 20 and 21, splines 45 causing said sleeves 21 and 20 to rotate with the shafts 41 and 42, but permitting the longitudinal reciprocatory movement of the shafts within the sleeves.
- The cross head 40 is connected to the reciprocating cutter carrier 30 and also to the other reciprocating cutter carrier 35^b, whereby the cutter carriers 30 and 35^b reciprocate upon their bearings in the head 11 to cause the cutters 31 and 35 to cut out the pieces of the flange on either side of the web in cooperation with the cutters 25 and 27.
- In accordance with one feature of the invention, means are also provided for rendering either one or both the cutters for either side of the flange operative or inoperative, as may be desired, and such means are preferably embodied in the reciprocatory connections, and are settable either one way or the other at the option of the operator of the machine. In the embodied form of such means, a wedge or gag 46 is slidably mounted in the cross head 40 and in the cutter carrier 30. The wedge 46 is provided with a T-shaped head 47 working in a similar groove in the cross head 40 and with a T-shaped head 48, fitting into a groove or slot in the cutter carrier 30. Fixed to the wedge or gag 46 is a rod 50, screw threaded into nut 52 journaled in a bracket 51 carried upon the machine frame, and provided with a convenient hand wheel. Thus the gag or wedge 46 may be slid backward and forward, thereby retracting the cutters from the cutting position or moving them forward into cutting position as desired. A similar controlling device is provided for the other cutter, and the parts thereof are designated by similar reference numerals and need not be described in detail.
- Means are provided for increasing or decreasing the distance between the groups of

4

cutters for both sides of the beam to accommodate beams of different sizes. As embodied the shafts 41 and 42, at the other end thereof are provided with screw threaded portions 62 and 63 respectively. Upon said screw threaded portions is mounted a cross head 64, having apertures therein through which the shafts 41 and 42 pass, said apertures being internally threaded to engage respectively with the screw threads 62 and 63 upon the shafts 41 and 42. The cross head 64 is connected by a wedge 46^c with a cutter carrier 30^a and is also connected by a wedge 46^c with a cutter carrier 35^c. The head 15 is mounted to slide on guides 10^a and 10^b, the cross head 64 is slidably mounted between the guides 10^a above and guides 10^b below. The cutter carrier 35^c is slidably mounted above guides 10^b and cutter carrier 30^a is mounted upon cutter carrier 35^c and beneath guides 10^a, and is adapted to slide with or upon cutter carrier 35^c. Means are provided for rotating the shafts 41 and 42 together, to regulate the distance between the heads 11 and 15, and the screw threads upon the sleeves 21 and 20 and the screw threads 62 and 63 upon the shafts 41 and 42 are proportioned to keep the cross head 64 in proper position, or uniformly spaced away from the head 15. The embodied form of means for rotating the shafts 41 and 42 is manually operable, and comprises a sprocket wheel 65 upon shaft 41 and a sprocket wheel 66 upon shaft 42. A sprocket chain 67 passes thereover and a hand wheel 68 is fixed upon the shaft 41.

Means for operating the cutters to cut the beam are provided, and in the embodied form thereof the reciprocable cross head 40 is pivotally connected to a pitman 70, said pitman being also pivotally connected to a double crank 71 formed in shaft 72, which shaft is mounted upon the machine frame. Means are provided for intermittently operating the mechanism as desired, and in the embodied form thereof a gear 73 is fixed to the shaft 72. Meshing with the gear 73 is a pinion 74 upon a shaft 75. Fixed to rotate to the shaft 75 is a clutch member 76, said clutch member rotating with but being free to slide upon the shaft 75. Mounted loosely upon shaft 75 is a gear 77, meshing with a pinion 86 upon the shaft of a motor 78. Fixed on gear wheel 77 is a clutch member 79, coöoperating with the movable clutch member 76. Clutch member 76 is urged into engagement with clutch member 79 by a spring 80, which spring is coiled about shaft 75 between the clutch member 76 and a bearing 81. Formed in the clutch member 76 is a cam groove 82 and coöoperating therewith is a pin 83 which is projected into and withdrawn from the cam groove to control the driving action of

the motor 78 upon the shaft 75. The pin 83 is pressed into the slot by spring 84 and retracted therefrom by a solenoid 85. In the present embodiment, the pinion 74 and gear wheel 73 are in the ratio of four to one, although this is immaterial so far as regards many features of the invention.

In the embodied form of means for making the cut or cuts in the web of the beam (Figs. 1, 2, 4, 7, 8, 12 and 15), the cutter 35 is vertically reciprocable in its carrier 35^b to make the cut in the web. The embodied form of actuating means therefor comprises a bar 90 (see especially Figs. 4, 7 and 8) which bar is reciprocably mounted in the head 11, the cutter 35 resting upon the upper end of the bar. The lower end of the bar 90 rests upon a cam 91, which cam is rotatable with but slidably along a shaft 92. The bar 90 and cam 91 are kept together by suitable means, such as a tongue 93 on the bottom of the bar projecting into a groove 94 formed in the face of the cam 91. A similar construction of reciprocable cutter and actuating means therefor is provided for the other side of the machine for making the cut in the other side of the web, and the corresponding parts are indicated by reference numerals 90^a to 94^a, and need not be described in detail. Fixed to the shaft 92 is an arm 99 carrying a weight 100.

Fixed on shaft 92 is a gear 101, meshing with a pinion 102 on a shaft 103. The ratio of pinion 102 and gear 101 is preferably four to one, as in the case of the pinion 74 and gear 73. Rotatable with but slidable along the shaft 103 is a clutch member 104. Carried loosely upon shaft 102 is a gear 105 driven from a pinion 106 on the shaft of a motor 107. Fixed to the gear 105 is a clutch member 108 adapted to coöperate with the clutch member 104. The clutch member 104 is urged into engagement with clutch member 108 by spring 109, and the engagement and disengagement of the clutch members is effected and controlled by the cam groove 110 in the clutch member 104 and the pin 111 which coöperates with said groove. The pin 111 is acted on by spring 112 and solenoid 113 in substantially the manner already described in connection with the clutch mechanism 76—79.

Referring to Fig. 1 of the drawings there is shown at the right a diagrammatic arrangement of circuits whereby the solenoids for the clutch mechanisms are operated from a distance record sheet or other controller sheet 170. The various contacts for the clutch controlling circuits are indicated by 171 and 172 and a suitable source of power 125 as 173. It will be understood that the clutch mechanism may be manually or otherwise operated if desired.

Means are provided for positioning and gaging the beam or shape both longitudi-

nally and transversely with reference to the notching and coping mechanism, and as embodied a guide rail 115 serves to position the beam transversely. The beam is positioned longitudinally by means of a movable stop, which is movable into and out of the path of travel of the beam, whereby it may position the beam to be operated upon, and then may be moved out of position to permit the beam to be carried away. Said stop is also adjustable to variously position beams of different sizes for notching and coping. As embodied a lever 116 is pivoted at 117 upon the machine frame. The end 118 of lever 116 is enlarged and internally screw threaded to take a screw threaded rod 119, the end of the rod 119 contacting with the end of the beam α (Fig. 1), and acting as a stop therefor. A hand wheel 120 serves to rotate screw rod 119 to regulate the position of the beam α .

The manner of operation of the mechanism which has already been described in large part, may be summarized as follows:

5 A beam α is fed into the machine, its transverse position being determined by the guide rail 115, and its longitudinal position being determined by the rod 119. The operation of the cutting devices is determined 25 and controlled in the illustrated and described mechanism by the pins 83 and 111, and these may be controlled manually or automatically as desired or arranged. If the solenoids 85 and 113 are placed in a 30 hand controlled circuit, push buttons could be utilized to operate each as desired, or the solenoids could be controlled from a perforated distance record sheet or other suitable automatic controlling device. When 35 pin 83 is retracted, clutch member 76 engages clutch member 79, and shafts 75 and 72 are started into rotation. The pin 83 being returned into groove 82 cams out the clutch after one rotation of shaft 75.

40 As the shaft 72 rotates, the connecting rod 70 will travel or reciprocate the groups of cutters which are on either side of the beam α . Let it be assumed that the cutters in Fig. 2 have taken up the clearance to the 45 right of the beam α and are ready to begin cutting the beam. Cutters 31 and 35 will pass from the position shown in Figs. 2, 9 and 10 to the positions shown in Figs. 6, 11 and 12. In so doing, one of the cutting 50 edges of the cutter 31 cuts off the flange along the web from the end of the beam, and another cutting edge of cutter 31 has co-operated with the cutter 25 to cut the side of the flange transversely from the cut along 55 the web to outside of the flange. Upon the other side of the web (the lower side in Figs. 10 and 12), a cutting edge 37 of cutter 35 has likewise cut off the flange along the web from the end of the beam, and 60 cutting edge 36 of cutter 35 has co-operated

with cutter 27 to make a like transverse cut in the flange from the cut along the web to the outside edge of the flange. This side of the beam is thus cut as shown in Figs. 11 and 12. It will also be understood that by 70 reason of the cutting edges of the cutter 31 being in advance of the cutting edges of the cutter 35, the cuts are made successively, and the entire power of the machine is thus available for each cut. By reason of the 75 four to one ratio of shafts 75 and 72, the clutch 76—79 is thrown out and the reciprocatory movement of the cutter is stopped with the cutters in position to cut or trim the web. 80

If it is desired to make the web cut at this time, the pin 111 is actuated to release clutch 104—108 for a revolution of shaft 103 thus imparting a quarter revolution to shaft 92. This partial revolution of shaft 92 85 moves cutter 35 vertically from the position shown in Fig. 12. By such vertical movement of the cutter 35, imparted through cam 91 and bar 90, the cutting edge 37 of cutter 35 and the cutting edge 33 of cutter 31 are moved to the position shown in Figs. 13, 14 and 15, thus making a beveled cut in the web of the beam from the cut in the flange to the end of the beam. When the finger 111 again throws out the clutch 104—95 108, after a single revolution of the shaft 103, and a quarter revolution of the shaft 92, the weight 100 rotates the shaft 92 backwardly and the cutter 35 returns to the position shown in Fig. 12 and is clear of the 100 web of the beam α . Another quarter revolution of shaft 72 withdraws the right hand cutters and brings the left hand cutters forward toward the work. During the first 105 described reciprocatory movement of the groups of cutters, the movable cutters at the left, (refer to Fig. 2), were moved away from their corresponding stationary cutters and no cutting was effected in that side of the machine. 110

When clutch 76—79 is again released, the rotation of shaft 72 will cause the groups of cutters on the other side of the beam (left hand in Fig. 2) to cut the beam, and the flange of the beam on the opposite side 115 is cut off in like manner to that already described by the cutters on the right hand side of Fig. 2. Upon the clutch 104—108 being again released the corresponding web cut on the left hand side of the beam is also 120 made. If it is desired to throw out any particular cutter, this can be done by the gags or wedges 46, etc.

The adjustments to accommodate beams of different sizes, have already been described and it will be understood that by rotating the shafts 41 and 42 together, the sleeves 20 and 21 will be correspondingly rotated, and said sleeves will consequently 125 pass into or out of the head 11. The head 130

- 15 will likewise be traveled along the sleeves 20 and 21, and the cross head 64 will maintain the movable cutters and cutter carriers in proper position with the head 15.
- 5 When the cutting of the beam is completed, it can be run backwardly by reversing the rolls 1, or it may be run in a forward direction by swinging up the stop rod 119.
- 10 In accordance with certain features of the invention, means are provided for simultaneously operating upon both ends of the beam, said means being constructed to accommodate beams of different lengths as 15 well as beams of different sizes. In the embodied form of such means, one beam cutting or coping device 130, which may be of like construction and operation as the mechanism already shown and described is provided, 20 same being in operative relation with a series of rollers 131, along which the beams or shapes are adapted to be traveled. A second beam cutting or coping device 132, which may likewise be of similar construction and operation as the mechanism herein 25 shown and described is provided. Means are provided for varying the distance between the mechanisms 130 and 132 for beams of different lengths, and as embodied the 30 mechanism or device 132 is movable along tracks 133 and 134, thereby to be brought into operative relation with one end of beams of varying lengths when the other end of any such beam is in operative relation 35 with the other mechanism or device 130. A driving motor 135 is provided connecting by gearing 136 with a shaft 137. The device 132 travels along the shaft 137 in being adjusted in various positions, but the mechanism 40 is driven by the rotation of the shaft in all its positions. At 138 and 139 are indicated means for supplying beams to, and for removing them from, the pathway of progressing means 131.
- 45 In Fig. 17 of the drawings is shown cooperating mechanism for supplying beams, cutting them into desired lengths, placing identifying marks upon the beams, and for forwarding the beam to coping devices or 50 punching devices or to both and for maintaining a reserve supply of beams when desired. In conjunction therewith means are provided for cutting or coping both ends of the beam, the coping or cutting mechanisms or devices being stationary. In the 55 embodied form, the beams are supplied from the rolling mill along the roller pathway 140 and are marked with identifying marks by the machine 141, which serves to 60 stamp in the hot beam the number and other identifying marks necessary to properly place the beam in the structure. A cutting mechanism 142 is provided, and operating therewith gaging stop devices 143 and 144, by which either or both ends of the

beam may be cut as desired. The beam is then forwarded along the pathway 145 and may be sent direct to the punching mechanisms 146, 147 and 148, to receive the rivet holes for fabrication, or the beams may be sent to the coping devices and have one or both ends coped and then be forwarded to the punching devices. A transferring means 150 for transferring the beams from pathway 145 to pathway 151 are provided. 70 In conjunction with pathway 151, a coping device 152 is shown adapted to cope one end of the beam, said device having a longitudinal stop or adjustment 153. After one end of the beam has been coped by this 80 mechanism, the stop 153 may be withdrawn and the beam run along the pathway 156 past the other coping device or mechanism 154, and the beam may then be brought into operative relation with the stop 155 preparatory to the coping of the beam by the mechanism 154. Upon completion of this 85 operation, the beam may be transferred by the mechanism 157 to the pathway 145 and thence to the punching devices 146, etc. In 90 conjunction with the foregoing there is provided transferring and storing devices 158 whereby the output from the mill may be stored preparatory to being either coped or punched for riveting and thus all the mechanisms may be run at full capacity, or any one may be stopped for adjustment or repair without affecting the operation and output of the others.

Means are provided by one feature of the 100 invention, for raising and lowering the rolls 1 for beams of different sizes. As embodied said rolls are carried together with their driving shafts and gears 160, upon frame 3 (Fig. 19). Said frame 3 is mounted on suitable raising and lowering devices, such as screw threaded rods 161, passing into internally screw threaded pillars 162. Screw rods 161 are rotated in either direction by bevel gears 163 meshing with bevel gear 164 110 on a shaft 165. Thus the rolls are raised and lowered as desired and the web of the beam centered with respect to the horizontal opening therefor between the cutters.

It will be understood that by the use of 115 the double beam cutting machines such as are provided by the invention, both ends of a beam may be notched and coped and prepared for joining for fabrication with great expedition, all the operations on both ends 120 of the beam being effected practically simultaneously, and the beam so prepared fed forward expeditiously for a succeeding operation, such as punching the rivet holes. By an arrangement of machines such as is 125 provided, a maximum operation of the various machines may be had without one machine being held up by the other.

From all the foregoing it will be understood that means and mechanisms have been 130

provided embodying and realizing the objects of invention and the advantages herein set forth, together with other objects and advantages. It will also be understood that 5 changes may be made from the mechanism and constructions shown and described without departing from the principles of the invention and without sacrificing its chief advantages.

10 I claim—

1. A machine for operating upon structural beams, including in combination a head carrying a group of cutters for one side of the beam, a head carrying a group of cutters for the other side of the beam, a shaft 15 connecting said heads, said shaft being movable to space the heads for beams of different sizes and to cause the cutters of each group to cut, one of said movements being 20 rotative and the other reciprocable.

2. A machine for operating upon structural beams, including in combination, a head carrying a group of cutters for one side of the beam, a head carrying a group 25 of cutters for the other side of the beam, a shaft connecting said heads, said shaft being movable to space the heads for beams of different sizes and to successively cause the cutters of each group to cut, one of said 30 movements being rotative and the other reciprocable.

3. A machine for operating upon structural beams, including in combination, a head carrying a group of cutters for one 35 side of the beam, a head carrying a group of cutters for the other side of the beam, a shaft connecting said heads, said shaft being rotatable to space said heads for beams of different sizes and being reciprocable to 40 cause each group of cutters to cut the beam.

4. A machine for operating upon structural beams, including in combination a head carrying a group of cutters for one side of the beam, a head carrying a group 45 of cutters for the other side of the beam, a shaft connecting said heads, said shaft being rotatable to space said heads, for beams of different sizes and being reciprocable to cause each group of cutters to successively 50 cut the beam.

5. A machine for operating upon structural beams, including in combination a head carrying a group of cutters for one side of the beam, a head carrying a group of cutters for the other side of the beam, a shaft 55 connecting said heads, said shaft being rotatable to space said heads for beams of different sizes and being reciprocable to cause each group of cutters to cut the beam, and 60 means for positioning the beam transversely with respect to the cutters.

6. A machine for operating upon structural beams, including in combination, a group of stationary cutters for one side of 65 the beam, a group of cutters for the other

side of the beam, and movable to and from said stationary group of cutters to accommodate beams of different sizes, and common connections between said groups of cutters, said connections being movable both to 70 move said movable group of cutters and to operate the cutters of each group to cut the flanges of the beam, one of said movements of said connections being rotative and the other reciprocable.

7. A machine for operating upon structural beams, including in combination a head carrying a group of cutters for one side of the beam, a head carrying a group of cutters for the other side of the beam, so a shaft connecting said heads, said shaft being movable to space the heads for beams of different sizes and to successively cause the cutters of each group to cut both flanges 85 of the beam, one of said movements being rotative and the other reciprocable.

8. A machine for operating upon structural beams, including in combination, a head carrying a group of cutters for one side of the beam, a head carrying a group of cutters for the other side of the beam, a shaft connecting said heads, said shaft being rotatable to space said heads for beams of different sizes and being reciprocable to cause each group of cutters to cut the flanges of 95 the beam.

9. A machine for operating upon structural beams, including in combination a head carrying a group of cutters for one side of the beam, a head carrying a group of cutters for the other side of the beam, a shaft connecting said heads, said shafts being rotatable to space said heads for beams of different sizes and being reciprocable to cause each group of cutters to successively cut the 105 flanges of the beam.

10. A machine for operating upon structural beams, including in combination a head carrying a stationary cutter and a movable cutter, a shaft having threaded engagement 110 with said head but being free to reciprocate longitudinally and a connection from said reciprocable shaft to said movable cutter to give it a cutting action in coöperating with said stationary cutter.

11. A machine for operating upon structural beams, including in combination, a head carrying a stationary cutter and a movable cutter reciprocably mounted, a shaft having threaded engagement with said head 120 but being free to reciprocate longitudinally and a connection from said reciprocable shaft to said reciprocable cutter to give it a cutting action in coöperation with said stationary cutter.

12. A machine for operating upon structural beams, including in combination a head carrying a stationary cutter and a movable cutter, a shaft rotatable and longitudinally reciprocable, a sleeve about said shaft and 130

- rotating with but slidable along said shaft, said sleeve having exterior threaded engagement with said head, and connections from said shaft to said movable cutter.
- 5 13. A machine for operating upon structural beams, including in combination a head carrying a stationary cutter and a reciprocable cutter, a shaft rotatable and longitudinally reciprocable, a sleeve about said shaft and rotating with but slidable along said shaft, said sleeve having exterior threaded engagement with said head, and connections from said shaft to said reciprocable cutter.
- 10 14. A machine for operating upon structural beams, including in combination a head carrying a stationary cutter and a movable cutter, a shaft rotatable and longitudinally reciprocable, a sleeve about said shaft and rotating with but slidable along said shaft, said sleeve having exterior threaded engagement with said head, and connections from said shaft to said movable cutter, and means for reciprocating said shaft.
- 15 15. A machine for operating upon structural beams, including in combination a head carrying a stationary cutter and a movable cutter, a shaft rotatable and longitudinally reciprocable, a sleeve about said shaft and rotating with but slidable along said shaft, said sleeve having exterior threaded engagement with said head, and connections from said shaft to said movable cutter, means for rotating said shaft.
- 20 16. A machine for operating upon structural beams, including in combination a head carrying a stationary cutter and a movable cutter, a shaft rotatable and longitudinally reciprocable, a sleeve about said shaft and rotating with but slidable along said shaft, said sleeve having exterior threaded engagement with said head, and connections from said shaft to said movable cutter, means for reciprocating said shaft, and means for rotating said shaft.
- 25 17. A machine for operating upon structural beams, including in combination, a head carrying a stationary cutter and a movable cutter, a second head carrying a stationary and a movable cutter, a rotatable and longitudinally reciprocable shaft, a sleeve about said shaft and rotatable with but slidable along the shaft, and connections from said shaft to said movable cutters to effect the cutting action by the longitudinal reciprocation of said shaft.
- 30 18. A machine for operating upon structural beams including in combination means for presenting a beam to be cut, and means for cutting the beam including coöperating cutters having flange cutting and web cutting edges, the cutters having relative movement in one direction to cut the flange and 60 in a transverse direction to cut the web.
- 35 19. A machine for operating upon structural beams including in combination means for presenting a beam to be cut and means for cutting the beam including two cutting members having common movement to cut the flange respectively on either side of the web, and having relative movement to cut the web.
- 40 20. A machine for operating upon structural beams including in combination cutting means including cutters located within the flange at either side of the web, cutters having common movement thereagainst to cut off the flange and having movement relative to each other to cut off the web.
- 45 21. A machine for operating upon structural beams including in combination cutting means including cutting members having three cutting edges for cutting the flange transversely and also along the web and for cutting the web, and actuating means therefor for moving said cutting members parallel to the web when cutting the flange.
- 50 22. A machine for operating upon structural beams including in combination cutting means including cutting members having three cutting edges for cutting the flange transversely and also along the web and for cutting the web, and means for moving said cutters in transverse directions to effect different cuts.
- 55 23. A machine for operating upon structural beams including in combination cutting means, including stationary transverse flange cutters located within the flange, and cutting members having cutting edges co-operating therewith to make the transverse cuts in the web and having longitudinal cutting edges for shearing the flange along the web, and having slanting cutting edges for cutting the web from the flange to the end of the beam, means for moving said cutting members to cut the flange, and means for moving them relatively to each other to cut the web.
- 60 24. A machine for operating upon structural beams including in combination a block recessed to receive the flange and a portion of the web of a beam, stationary cutters mounted on said block on the inside of the beam flange, and traveling cutters mounted on said block exteriorly to the beam flange and coöperating with said stationary cutters to cut off the flange transversely and coöperating with each other to cut off the web at a bevel.
- 65 25. A machine for operating upon structural beams including in combination a block recessed to receive the flange and a portion of the web of a beam, stationary cutters mounted on said block on the inside of the flange, traveling cutters mounted on said block and coöperating with said stationary cutters, said traveling cutters having flange cutting edges and web cutting edges, and

means for moving said cutters in transverse directions to effect the flange and web cuts.

26. A machine for operating upon structural beams including in combination means for presenting a beam to be cut, means for cutting the beam, including stationary cutters within the flange, traveling cutters on the exterior of the flange having cutting edges for cutting the flange transversely, 5 said cutting edges on either side of the web being staggered to effect successive cuts, said members having edges for cutting the flange along the web likewise staggered to effect successive cuts. 10

15 27. A machine for operating upon structural beams including in combination means for presenting a beam to be cut, means for cutting the beam including stationary cutters within the flange, traveling cutters on the exterior of the flange having cutting edges for cutting the flange transversely, 20 said cutting edges on either side of the web being staggered to effect successive cuts, said members having edges for cutting the flange along the web likewise staggered to effect successive cuts, 25 said members also having beveled web cutting edges, and means for moving said movable cutters in the same direction to cut the flanges and for moving them together to shear the web between them. 30

28. A machine for operating upon structural beams including in combination two blocks, each recessed to receive one of the 35 flanges and a portion of the web of a beam, each of said blocks being supplied with stationary cutters and movable cutters for cutting the flanges and the web of the beam and means for varying the distance between said 40 blocks to accommodate beams of different sizes.

29. A machine for operating upon structural beams including in combination two blocks, each recessed to receive one of the 45 flanges and a portion of the web of a beam, each of said blocks being supplied with stationary cutters and movable cutters for cutting the flanges and the web of the beam, and means for changing the relative positions of the cutters on the block. 50

30. A machine for operating upon structural beams including in combination a block recessed to receive the flange and part of the web of a beam, an opposing block recessed to receive the other flange and part 55 of the web of a beam, stationary cutters upon said blocks within the flanges of the beam and cutters on the exterior of the beam

flanges reciprocably mounted upon said respective blocks.

60

31. A machine for operating upon structural beams including in combination a block recessed to receive the flange and part of the web of a beam, an opposing block recessed to receive the other flange and part 65 of the web of a beam, stationary cutters upon said blocks within the flanges of the beam flanges reciprocably mounted upon said respective blocks, and means for changing the 70 relative position of said blocks to accommodate beams of different sizes.

32. A machine for operating upon structural beams including in combination a block recessed to receive the flange and part of the 75 web of a beam, an opposing block recessed to receive the other flange and part of the web of a beam, stationary cutters upon said blocks within the flanges of the beam, cutters on the exterior of the beam flanges reciprocably mounted upon said respective blocks, and means for reciprocating said cutters to alternately cut the flanges of the beam. 80

33. A machine for operating upon structural beams including in combination a block 85 recessed to receive the flange and part of the web of a beam, an opposing block recessed to receive the other flange and part of the web of the beam, stationary cutters upon said blocks within the flanges of the beam 90 and cutters on the exterior of the beam flanges mounted to move upon said blocks in transverse directions to cut both the flanges and web of the beam.

34. A machine for operating upon structural beams including in combination means for presenting a beam to be cut, means for cutting the beam including stationary cutters within the flange, traveling cutters on the exterior of the flange having cutting 100 edges for cutting the flange transversely, said cutting edges on either side of the web being staggered to effect successive cuts, said members having edges for cutting the flange along the web likewise staggered to effect 105 successive cuts, said members also having beveled web cutting edges, and means for moving said movable cutters in transverse directions to effect the flange and web cuts.

In testimony whereof, I have signed my 110 name to this specification, in the presence of two subscribing witnesses.

EDWARD V. WURTS.
